UNITED STATES PATENT OFFICE.

EDWIN LANE, OF NEW YORK, N. Y., ASSIGNOR TO CAROLYN LAUNDRY, OF NEW YORK, N. Y., A CORPORATION OF NEW YORK.

LAUNDRY CHECK.

Original application filed April 24, 1925, Serial No. 25,593. Divided and this application filed November 16, 1925. Serial No. 69,555.

The present invention relates to certain novel and useful improvements in checking devices, and has particular application to a laundry marker or tag adapted to be attached to garments and other pieces or articles for the purpose of identifying the pieces belonging to each customer, so that such pieces may be segregated, laundered, and re-collected without loss or confusion.

10 This application is a division of my co-pending application for laundry checking devices, filed April 24, 1925, Serial No. 25,593.

15 Heretofore, various forms of laundry checks or tags, have been suggested, such as those wherein an ordinary safety pin is attached to the tag, and those wherein the tag is in the nature of a relatively thick multiply clamping plate of metal, usually requiring a 20 special tool for applying it to the piece or article to be laundered.

25 To such forms of tags or markers, certain disadvantages are incident. For example, in the markers employing the safety pin arrangement, the pin is usually required to be of such size that in penetrating the garment or other article it forms a relatively large perforation, and in addition is liable to become entangled with the fabric in the 30 laundering operations, and frequently tears or damages the garment. In case of the multiply metal clamping plates, these also are generally of such size and thickness as to require special prongs to maintain the 35 plate in clamping relation to the piece being laundered, and consequently also present the liability of tearing or injuring such piece.

40 In the present instance, I aim to obviate these disadvantages by providing a relatively thin flat plate provided with small perforations by means of which the marker may be stitched either by hand or machine to the article to be laundered. Furthermore, such 45 flat thin plate is provided with an identifying number or character and also with the key-way by means of which the check or marker, when not in use, may cooperate with and be applied to a key bar or rod of proper configuration, so that all similarly 50 numbered or identified tags may be strung upon a proper or complementary key bar, thereby avoiding confusion in the distribution of the tags, and consequently in the sorting of the laundered pieces.

Another important object of the invention 55 resides in the provision of a laundry marker having attaching means associated therewith in such a manner that at least one of the attaching means will be disposed in position for immediate attachment to a laundry 60 piece regardless of how the marker is held while being picked up and applied to the laundry piece.

With the above recited objects and others 65 of a similar nature in view my invention consists in the construction, combination and arrangement of parts set forth in and falling within the scope of the appended claims.

In the drawings—

Fig. 1 is a perspective view of a plurality 70 of my key markers threaded upon a complementary key bar;

Fig. 2 is a perspective view of the tag or marker.

Referring now to the accompanying drawings in detail, and particularly to the tag or marker itself, the numeral 1 indicates the body of the tag which is in the nature of a single flat piece of sheet metal which may be of rectangular form shown, or of other 80 suitable shape. The check opening 2 is formed centrally in this flat single plate having key-corresponding slots 3 and an identifying number or character 4—it being understood that all checks bearing the same 85 identifying character or number are for use in connection with the batch of articles or pieces of a particular customer. The marker or plate is also provided with a plurality of minute thread holes 5 located preferably near 90 the corners, and entirely around the slot 3.

The disposition of the thread holes or attaching device 5 of the marker is of great importance in that it facilitates the work of an operative in securing the markers to the laundry pieces. It will be observed that these thread holes 5 are arranged at the four corners of the marker so as to totally surround the check opening 2.

Due to this arrangement, it will be obvious 100 that the operative can with great facility pass a thread through one or more of the thread holes 5 and the laundry piece, regardless of the position in which the marker is held while being picked up and applied 105 to the laundry piece. This is also the case, even though the markers are not held in a predetermined relationship, as when they

are simply loosely scattered in a suitable receptacle. The number of thread holes by which the marker is attached to a laundry piece depends upon how much of the marker 5 overlaps the laundry piece when applied thereto for sewing, for if only one corner of the marker overlaps the laundry piece only the thread hole 5 in that corner will be employed for attaching the marker. On the 10 other hand, if the marker happens to be applied to the laundry piece so that two or more of the thread holes overlap the laundry piece, all of the thread holes or as many as desired may be employed in the attachment 15 of the marker by passing a thread through one or more of the thread holes and the laundry piece. In previously known laundry markers or tags the thread holes or attaching means have been located only at one end 20 of the same, which arrangement results in a loss of time in the application of the tags to laundry pieces, due to the fact that the operative must turn or adjust the tag so that its thread holes overlap the garment to 25 which it is to be attached. With applicant's arrangement of thread holes the loss of time incident to the manipulation and adjusting of the tags is entirely eliminated, which obviously results in an enormous saving of 30 time when the large quantity of such markers used in an up-to-date laundry is considered.

In Fig. 1, I have shown a key bar 6, fastened by a suitable bracket 7 to a wall or other support, this key bar having ribs 8, cooperating in location and form with the key aperture in flat plate-like marker or check, so that a particular marker or check may be strung or fitted upon the key bar. 35 The rib and key slot arrangement of the bar and markers or checks may be arranged in almost unlimited permutations, a different cooperative formation being provided for each key bar and its set of identically numbered markers, so that the sorter need depend on numbers or marking characters only as a guide to a particular sorting compartment at which the appropriate key bar is located, and then when placing the fabric 40 in the compartment the check or key opening of the marker is passed over the key, and the fitting of the key shows that the identification of the garment or fabric is correct, and failure of a particular marker or check 45

to fit upon particular key bar shows that 55 an error has been made, which is then corrected by re-inspection of the identification character or number.

It will be noted that the flat plate when 60 stitched to the garment or other article may be placed inward of the edge thereof, if desired, and stitched in such position, and being thin and flat will form no projecting part of consequence to catch in the laundering machine or to cause trouble in other 65 ways. Furthermore, there are no projecting metal parts or clamping device or pins for catching and tearing the article to which the check is attached.

70 I claim:

1. A marker check for the purpose described, comprising a substantially flat plate having a plurality of laundry piece attaching means located at spaced points entirely around the edges of the plate whereby at 75 least one of said attaching means is in proper position to be attached to a laundry piece in the same position it is picked up, and regardless of the position it is held in when it is picked up to be attached to said laundry 80 piece.

2. A marker check for the purpose described, comprising a substantially flat plate having a central key-way therein, and a plurality of thread perforations located at 85 spaced points entirely around said key-way, whereby at least one of said perforations is in proper position to receive means for attachment of the check in the same position it is picked up and regardless of the position 90 it is held in when it is picked up to be attached to said laundry piece.

3. A marker check for the purpose described, comprising a substantially flat rectangular plate of a single ply of metal having 95 a key perforation therein, an identifying character thereon, said plate having a thread perforation at each of its corners whereby at least one of said thread perforations is in proper position to receive laundry piece attaching means in the same position it is picked up and regardless of the position it is held in when it is picked up 100 to be attached to said laundry piece.

Signed at New York in the county of New 105 York and State of New York this 23rd day of September, A. D. 1925.

EDWIN LANE.
